DIGITAL CLOCK

James R. Powers, Los Angeles, Calif., assignor to Ropat-Caslon, Inc., El Segundo, Calif.

Filed Nov. 3, 1972, Ser. No. 303,639

Term of patent 7 years

Int. Cl. D10—01

U.S. Cl. D10—15

FIG. 1

FIG. 2

FIG. 3

FIG. 4

FIG. 5

FIG. 6

FIG. 7

FIG. 1 is a perspective view of a digital clock showing my new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and

FIG. 7 is a bottom plan view thereof.

I claim:

The ornamental design for a digital clock, as shown.
